CLAUDE M. PADGETT, OF CHICAGO, ILLINOIS, ASSIGNEE OF ONE-HALF TO VIVIAN DICK
TENNYSON, OF CHICAGO, ILLINOIS.

SELF-HEATING SOLDERING-TOOL.

1,333,590.

Specification of Letters Patent.

Patented Mar. 9, 1920.

Application filed May 8, 1919. Serial No. 295,677.

To all whom it may concern:

Be it known that I, CLAUDE M. PADGETT, a citizen of the United States, residing at Chicago, in the county of Cook and State 5 of Illinois, have invented new and useful Improvements in Self-Heating Soldering-Tools, of which the following is a specification.

This invention relates to soldering tools 10 which are self-heated, a liquid fuel burner being provided which is a part of the tool.

The invention has for its object to provide a simple, efficient and economical tool of the kind stated, and to this end it consists in a 15 novel combination and arrangement of parts to be hereinafter described and claimed.

In order that the invention may be better understood, reference is had to the accompanying drawing, forming a part of this 20 specification.

In the drawing,

Figure 1 is a side elevation of the tool, with parts in section;

Fig. 2 is a cross-section on the line 2—2 of 25 Fig. 1, and

Fig. 3 is a plan view of the tool with a portion of the handle broken away.

Referring specifically to the drawing, 5 denotes the handle of the device, the same 30 being hollow so as to serve as a liquid fluid reservoir. The outer end of the handle is fitted with a screw plug 6 which is removable to permit filling of the reservoir. The liquid fuel is forced from the reservoir by 35 air pressure as usual, an air pump 7 being carried by the plug 6. The barrel of the pump is located in the reservoir and has an outlet tube 8 which discharges near the top of the reservoir.

To the forward end of the reservoir 5 is connected a fuel discharge pipe 9 into which a wick 10 extends for conducting the liquid fuel thereinto when the device is inclined or in an upright position. The fuel will feed 45 itself when the device is placed horizontally. The discharge pipe 9 leads to a circular pipe or tube 11 formed integral with, and on the outside of a mixer tube or chamber 12 intermediate the ends of the latter. The tube 12 has perforations 13 in its side for the entry of air, and its outer end is closed by the soldering iron tip 14, the same being pointed as usual. The tip 14 screws into the tube 12 as shown in Fig. 1, and closes 55 the outer end thereof. The inner end of the

tip 14, inside the tube 12, has a central cavity 15 terminating in lateral branches 16, which open through the sides of the tip, back of its point.

Into the rear end of the mixer tube 12 60 opens a fuel delivery pipe 17 carrying a needle valve 18 for controlling the discharge of fuel into the tube. The pipe 17 is in longitudinal alinement with the tube 12 and positioned centrally thereof. The pipe 11 65 encircles the tube 12 intermediate its ends and back of the perforations 13, and to the rear of the pipe 11, the tube 12 has two diametrically opposite air-inlet openings 19 shown dotted in Fig. 1. These openings are 70 triangular and so arranged that when the tool is propped up in inclined position, as shown in Fig. 1, the bottom edges of the openings are horizontal. This permits a sufficient amount of fuel to be discharged 75 into the rear end of the tube 12 for starting the burner, by applying a match at one of the openings.

At a point diametrically opposite where the pipe 9 connects with the pipe 11, a rearwardly extending branch pipe 20 connects the latter with the pipe 17.

The air openings 19 are protected from drafts by shields or wings 21 extending rearward from the pipe 11.

When the torch is burning to heat the tip 14, preparatory to the use of the tool, the same is supported by a pair of props 22 pivoted to ears 23 on the bottom of the pipe 9. The props are foldable alongside the pipe 90 9, as shown dotted in Fig. 1, in which position they are held by side spring clips 24 on said pipe.

The forward end 25 of the pipe 9, serves 95 as a vapor generator, and a further vaporization of the fuel takes place in the pipe 11. The vapor is discharged past the needle valve 18 into the mixing tube 12 where it mixes with the air entering through the openings 19 and 13, and upon being ignited 100 at the openings 16 it burns with an intensely hot flame around the tip 14, so that the latter is quickly heated. The valve 18 can then be partly closed to reduce the flame, and the tool is ready for use. The tool is propped 105 up as shown in Fig. 1 while the tip is being heated, and when not in use, or while being used, the props 22 can be swung back and so held by the clips 24 as shown dotted.

The parts, 11, 12, 17, 20 and 25 may all 110

be made in one piece. The pipe 9 screws into the part 25 and the latter is a continuation thereof.

The tool is simple and compact in construction, and also economical in fuel consumption, as the fuel is completely vaporized in its passage through the pipes 25 and 11, the same therefore serving as a retort. The tube or pipe 11 is kept very hot as it is 10 integral with the mixing tube or chamber 12.

I claim:

1. In a self-heating soldering tool of the liquid fuel burner type, a mixing chamber having side air inlets, a soldering tip connected to the forward end of the chamber and having side burner apertures leading from the chamber, a retort tube integral with the mixing chamber and encircling the same externally, intermediate its ends, the 15 air inlets being in advance of and to the 20

rear of the tube, wind shields over the rear air inlets, a fuel delivery pipe to the retort tube, and a connection between the retort tube and the mixing chamber.

2. In a self-heating soldering tool of the 25 liquid fuel burner type, a mixing chamber having air inlets, a soldering tip connected to the forward end of the chamber and having burner apertures leading from the chamber, a retort tube integral with the mixing 30 chamber and encircling the same externally, diametrically opposite fuel pipes on the outside of the mixing chamber extending rearwardly from the retort tube and integral therewith, a supply connection to one of the 35 pipes, and a valved connection between the other pipe and the rear end of the mixing chamber,

In testimony whereof I affix my signature.

CLAUDE M. PADGETT.
